UNITED STATES PATENT OFFICE.

CHARLES H. D. SINCENTES, OF MONTREAL, CANADA.

STEP-LADDER.

SPECIFICATION forming part of Letters Patent No. 469,751, dated March 1, 1892.

Application filed November 27, 1891. Serial No. 413,334. (No model.) Patented in Canada November 6, 1891, No. 37,741.

To all whom it may concern:

Be it known that I, CHARLES HERCULE DAMASE SINCENTES, of the city of Montreal, in the district of Montreal and Province of 5 Quebec, Canada, have invented certain new and useful Improvements in Safety Rolling Step-Ladders, (for which I have secured Letters Patent in Canada November 6, 1891, No. 37,741;) and I do hereby declare that the following is a full, clear, and exact description of said invention.

The invention consists in an improved construction of rolling step-ladders, whereby they are rendered safer, more durable, and less expensive in their manufacture. I combine with the shelving an upper and lower guide-railing presenting unobstructed traveling surfaces along their bottom and top edges, respectively, and carry upper and lower grooved 15 rollers on the ladder, so that they shall travel along the under side and upper side, respectively, of said guide-railings. For full comprehension, however, of the invention, reference must be had to the accompanying drawings, forming a part of this specification, in which like symbols indicate corresponding parts, and where—

Figure 1 is a perspective view of my step-ladder in position, and Fig. 2 a side elevation 20 of the same.

A is the top board of the shelving; B, the usual counter-ledge of the same, and A' B' rods or rails secured along the underside and top, respectively, of such board and ledge.

C is the step-ladder, of any ordinary construction and carrying in metal shoes D D, on the upper ends of its side bars, grooved rollers D' D', which travel along under the rail A'. A proper support E, preferably 35 formed of two arms e e, suitably braced and carrying grooved rollers E' E' at one end to travel on the rail B' and having their opposite ends rigidly secured to the ladder about midway of its length, is used to support it 40 above ground and at the angle most convenient for use.

It will be apparent that this ladder, being confined between the upper and lower guide-rails, on the latter of which it is supported, 45 will always run smoothly, as its whole weight

is supported from below, and it cannot possibly be dislodged by accident.

I am aware that step-ladders carrying upper rollers to travel along an upper railing and lower rollers at their bottom ends to travel 55 along a rail placed on the floor some distance from the shelving are in use, and I therefore lay no claim to such construction.

What I claim is as follows:

1. The combination, with store - shelving 60 and upper and lower guide-rails running longitudinally along the face of the same respectively at the top and midway to the bottom, the upper rail having a vertical downward projection, of a step-ladder provided 65 with upper and lower rollers having traveling connection with and being spaced to the exact gage of said guide-rails, the upper rollers being vertical and grooved to receive said downwardly-projecting rail, substantially as 70 described.

2. The combination, with store - shelving and rails running longitudinally along the face of the same at the top and midway to the bottom and presenting unobstructed travel- 75 surfaces along their bottom and top sides, respectively, the upper rail having a vertical downward projection, of a step ladder provided with upper and lower vertical rollers having traveling connection with and being 80 spaced to the exact gage of said guide-rails, substantially as described.

3. The combination, with store - shelving and rails running longitudinally along the projecting top board and the counter-ledge 85 of the same and presenting unobstructed traveling surfaces along their bottom and top edges, respectively, the upper rail having a vertical downward projection, of a step-ladder carrying vertical grooved rollers 90 at its upper end adapted to receive such downward projection of the top board rail, and a support carried by the ladder and projecting rearwardly to the counter-ledge rail, with the top traveling surface of which it has a trav- 95 eling connection, as set forth.

4. The combination, with store - shelving provided with upper and lower guide-railing carried by such shelving and presenting un- 100 obstructed traveling surfaces along their bot-

tom and top edges, respectively, the upper rail having a vertical downward projection, of a step-ladder carrying vertical rollers having traveling connection with the said bottom 5 and top edges of such railing.

5. The combination, with store-shelving, of an upper and lower horizontal railing carried on the face of such shelving, respectively near the top of the same and about midway 10 to the bottom, the upper rail having a vertical downward projection, and a step-ladder carrying on each of its side bars two vertical grooved rollers, one of which is located near the top and adapted to receive such down- 15 ward projection of said upper railing and the other located about midway to the bottom

and adapted to travel along the upper side of the said lower railing, as shown and described.

6. The combination, with store-shelving, of an upper and lower guide-railing presenting 20 unobstructed traveling surfaces along their bottom and top edges, respectively, the upper rail having a vertical downward projection, and a step-ladder carrying on each of its side bars upper and lower vertical grooved rollers 25 respectively adapted to travel along the under side and upperside, respectively, of said guide-railings.

CHARLES H. D. SINCENNES.
